(57) **CLAIM**

The ornamental design for a food based homogenizer, as shown and described.

DESCRIPTION

FIG. 1 is a first perspective view of a food based homogenizer, showing the new design.

FIG. 2 is a front-side view of thereof.

FIG. 3 is a rear-side view thereof.

FIG. 4 is a left-side view thereof.

FIG. 5 is a right-side view thereof.

FIG. 6 is a top-side view thereof.

FIG. 7 is a bottom-side view thereof; and,

FIG. 8 is a second perspective view thereof.

The broken lines shown in the drawings are for illustrative purposes only and form no part of the claimed design.
